[57] ABSTRACT

An electronic tremolo effect producing device in which a musical sound signal frequency is deviated by as much as frequencies of two signals having different frequencies each sufficiently lower than that of said musical sound signal by means of two frequency deviation devices. Respectively a part of the output signal of each frequency deviation device mentioned above is fed back to an input side of its own frequency deviation device or the other frequency deviation device thereby to obtain a multiple spectrum signal and this signal is mixed with an original musical sound signal thereby to produce a tremolo effect sound.

FIG. 1

FIG. 2

FIG. 3

FIG. 4

FIG. 5

ELECTRONIC TREMOLO EFFECT PRODUCING DEVICE

BACKGROUND OF THE INVENTION

This invention relates generally to an electronic tremolo effect producing device and more particularly to a type of device for creating tremolo effect sounds in a purely electronic manner.

Heretofore, there have been used tremolo or chorus producing devices wherein an electrical musical sound signal (as carrier wave) is amplitude-modulated with a signal (as a modulating wave) having a desired frequency and waveform, or as an alternative method, an electrical signal is converted into a sound signal through a loudspeaker rotating at a desired speed. (Hereinafter as far as an electric musical instrument is concerned a tremolo effect represents a modulation by a frequency ranging from 5 Hz to 10 Hz, while a chorus effect represents a modulation by a frequency ranging from 0.5 Hz to 2 Hz.). However, in the first mentioned system, since only amplitude modulation is employed, the frequency of the musical sound signal remains unchanged and therefore the resultant sound is rather monotonous and the sound effect is very poor. On the other hand, in the second system, the "Doppler effect" is produced in the musical signal by the rotation of loudspeaker, and as a result the frequency and phase of the musical sound signal are varied and the signal level is also varied with the variation of directivity whereby a wide spread sensation can be obtained. The second system is very effective, but however involves disadvantages such as an excessively complicated rotating mechanism and driving mechanism of the loudspeaker and a high production cost thereof. Furthermore, there are possibilities of various undesirable noises such as wind noise and other mechanical noises being introduced into the output at the time of rotation of the loudspeaker.

SUMMARY OF THE INVENTION

It is accordingly a primary object of the present invention to provide a novel organization of a tremolo or chorus effect producing device wherein all of the above-described drawbacks of the conventional devices can be eliminated.

Another object of the present invention is to provide a tremolo effect producing device wherein a tremolo effect which is very effective and rich in natural sound sensation can be obtained in a purely electronic manner.

A further object of the present invention is to provide a tremolo effect producing device which simulates substantially a multi-rank sound source.

A still further object of the present invention is to provide a tremolo effect producing device wherein a tremolo effect sound can be produced or stopped at an instant.

More specifically, it is an object of the present invention to provide a novel tremolo or chorus effect producing device which can operate in a purely electronic manner and is simple in organization and economical in production.

The nature, utility and the principle of the invention will be more clearly understood from the following detailed description with reference to the accompanying drawings.

BRIEF DESCRIPTION OF THE INVENTION

In the accompanying drawings:

FIG. 1 is a block diagram illustrating a principle of the tremolo effect producing device according to the present invention;

FIG. 2 is a block diagram showing an example of the frequency deviation device included in FIG. 1;

FIG. 3 exhibits an example of the frequency spectrum of a signal obtained in the tremolo effect producing device according to the present invention;

FIG. 4 is a block diagram of another embodiment of the tremolo effect producing device according to the present invention; and

FIG. 5 illustrates a frequency spectrum of a signal obtained in the tremolo effect producing device shown in FIG. 4.

DETAILED DESCRIPTION OF THE INVENTION

With reference now to FIG. 1 which is a schematic block diagram illustrating an example of the electronic tremolo effect producing device according to the present invention, reference symbol MS represents a musical sound signal circuit adapted to generate a musical sound signal (the signal usually comprises a plurality of frequency components thus constituting a frequency spectrum band and the fundamental frequency thereof is varied in accordance with the progression of the musical performance, but for convenience in explanation in this specification, the musical signal is represented by only a single frequency of f Hz) and frequency deviation devices FS₁ and FS₂ serve to deviate the frequency (f) of the musical sound signal by as much as a frequency (approximately 0.5 – 10 Hz) of Δf_1 and of Δf_2 respectively, both of which are sufficiently lower than the frequency (f). The positive sign (+) of $+\Delta f_1$ means that the frequency (f) is deviated higher by as much as Δf_1 , while, in the same way, the negative sign (-) of $-\Delta f_2$ means that the frequency (f) is deviated lower by as much as Δf_2 . Reference symbols FB₁ and FB₂ represent feed-back devices. The feed-back device FB₁ is connected between an output terminal k of the frequency deviation device FS₁ and an input terminal j of the frequency deviation device FS₂, while the feed-back device FB₂ is connected between an output terminal l of the frequency deviation device FS₂ and an input terminal i of the frequency deviation device FS₁. The feed-back devices FB₁ and FB₂ may be of a well known type, and can have a desired frequency characteristic. Reference symbols R₁ through R₅ are resistors for mixing of signals.

In FIG. 2 which exhibits a schematic block diagram of an example of the frequency deviation device shown in FIG. 1, the frequency deviation device comprises; a phase separator PS which is adapted to convert an input signal into two output signals which are 90° different in phase from each other; an extremely low frequency oscillator LFO which simultaneously generates signals having extremely low frequencies Δf_1 and Δf_2 which are sufficiently lower than that of the input of the phase separator (i.e., the musical sound signal having frequency f) and which are 90° different in phase from each other; modular M₁ and M₂ which serve to amplitude-modulate the extremely low frequency signals (as carrier waves) furnished from terminals d and e of the extremely low frequency oscillator

LFO with musical sound signals (as modulating waves) furnished from terminals *b* and *c* of the phase separator PS, respectively, and a high-pass filter F adapted to eliminate the extremely low frequency signal component (i.e. the carrier component) from the modulation output signal of each modulator. But, when balanced modulators are employed for the modulators *M*₁ and *M*₂, the filter F is not required.

Now, it is assumed that a musical sound signal at the output terminal *c* of the phase separator lags by 90° than that at the terminal *b* in phase and a carrier signal at the output terminal *e* of the extremely low frequency oscillator LFO also lags by 90° than that at the terminal *d* in phase, signals at terminals *b*, *c*, *d*, and *e* are represented by the following formulas:

$$\text{Terminal } b: a \cos \omega t \quad (\omega = 2\pi f)$$

$$\text{Terminal } c: a \sin \omega t \quad (\omega = 2\pi f)$$

$$\text{Terminal } d: A \cos \Delta \omega t \quad (\Delta \omega = 2\pi \Delta f)$$

$$\text{Terminal } e: A \sin \Delta \omega t \quad (\Delta \omega = 2\pi \Delta f)$$

Therefore, when the signal at the terminal *d* is amplitude-modulated with the musical sound signal at the terminal *b* in the modular *M*₁, the resultant modulation output signal can be represented by the following formula:

$$M_1 \text{ output} = A \cos \Delta \omega t + (mA/2) \{ \cos(\omega + \Delta \omega)t + \cos(\omega - \Delta \omega)t \}$$

where *m* = *kd* indicates the amplitude modulation factor (*k* is the modulation sensitivity).

In the same way, when the signal at terminal *e* is amplitude-modulated with the signal at terminal *c* in the modulator *M*₂, the resultant modulation output signal is represented by the following formula:

$$M_2 \text{ output} = A \sin \Delta \omega t - (mA/2) \{ \cos(\omega + \Delta \omega)t - \cos(\omega - \Delta \omega)t \}$$

These *M*₁ and *M*₂ output signals are combined at the input terminal of the high-pass filter F into a resultant signal represented by a formula shown below:

$$A (\cos \Delta \omega t + \sin \Delta \omega t) + mA \cos(\omega - \Delta \omega)t$$

$\Delta \omega$ component is removed by the high-pass filter F from this combined signal, whereby a signal of $a_1 \cos(\omega - \Delta \omega)t$ is obtained at an output terminal *k*(1) of the filter F (A phase shift due to the filter is disregarded.). The signal thus obtained is a deviated musical sound signal ($f - \Delta f$) which is lower by as much as the frequency Δf of the extremely low frequency oscillator LFO than the musical sound signal (f). Therefore, this is correspondent to $-\Delta f_2$ of the frequency deviation device FS₂ shown in FIG 1.

Next, if the signals to be applied to the modulators *M*₁ and *M*₂ respectively through terminals *b* and *c* are interchanged with each other, or the signals to be applied to the modulators *M*₁ and *M*₂ respectively through terminals *d* and *e* are interchanged with each other, a signal of $b_1 \cos(\omega + \Delta \omega)t$ is obtained at the output terminal of the high pass filter F. The signal thus obtained is a musical sound signal ($f + \Delta f$), the frequency of which is higher by as much as the frequency Δf oscillated by the extremely low frequency oscillator than the frequency (f), and this is correspondent to $+\Delta f_1$ of the frequency deviation device FS₁ shown in FIG. 1.

Therefore, when an oscillating frequency of the extremely low frequency oscillator LFO₁ in the frequency deviation device FS₁ is Δf_1 , and an oscillating frequency of the extremely low frequency oscillator LFO₂ of the frequency deviation device FS₂ is Δf_2 (but $\Delta f_1 \neq \Delta f_2$), if a part of the signal having the frequency ($f + \Delta f$) obtained at the terminal *k* of the frequency deviation device FS₁ is fed to the input terminal *j* of the frequency deviation device FS₂ through the feed-back device FB₁, and in the same way a part of the signal having the frequency ($f - \Delta f_2$) obtained at the terminal *l* of the frequency deviation device FS₂ is fed to the input terminal *i* of the frequency deviation device FS₁ through the feedback device FB₂, signal represented by the following formulas are obtained at the output terminals *k* and *l* respectively in the same way as mentioned before.

$$\text{Terminal } k: a_2 \cos(\omega + \Delta \omega_1 - \Delta \omega_2)t$$

$$\text{Terminal } l: b_2 \cos(\omega + \Delta \omega_1 - \Delta \omega_2)t$$

where a_2 and b_2 represent respective amplitudes. Further, each of these output signals is fed back to the input side of the other frequency deviation device which is different from the frequency deviation device from which the output has come out, whereby signals $a_3 \cos(\omega + 2\Delta \omega_1 - \Delta \omega_2)t$ and $b_3 \cos(\omega + \Delta \omega_1 - 2\Delta \omega_2)t$ are obtained at the output terminals *k* and *l* respectively. Thus, a signal having a frequency spectrum as shown in FIG. 3 is obtained. These signals are fed to the output terminal *m* through the resistors R₄ and R₅, and then are mixed with an original musical sound signal furnished through the resistor R₃. Then, the thus mixed signal is amplified properly and applied to a loud-speaker to produce a rich tremolo sound effected intricately by amplitude modulation, frequency modulation or phase modulation.

In the above description, the frequency characteristic of the feed-back devices FB₁ and FB₂ has not been explained. However, if the frequency characteristic of these said devices is made to have specially great attenuation in the low frequency regions, the envelope of a high frequency spectrum will be relatively widened in respect of the overall characteristic. This is more effective for a sound which is rich in higher harmonics as found in a musical string instrument. It is possible to select feed-back devices having various characteristics other than described above in order to obtain various effects on sound.

The above description relates to only such a case wherein the frequency deviation devices FS₁ and FS₂ cause respectively a frequency deviation of $+\Delta f_1$ and $-\Delta f_2$. However, if $\pm \Delta f_1$ and $\pm \Delta f_2$ are adopted as frequency deviations by utilizing two side band modulation devices, signals obtained at the terminals *k* and *l* are respectively

$$a_1 \cos(\omega \pm \Delta \omega_1)t + a_2 \cos(\omega \pm \Delta \omega_1 \pm \Delta \omega_2)t + a_3 \cos(\omega \pm 2\Delta \omega_1 \pm \Delta \omega_2)t - \text{ and } b_1 \cos(\omega \pm \Delta \omega_2)t + b_2 \cos(\omega \pm \Delta \omega_2 \pm \Delta \omega_1)t + b_3 \cos(\omega \pm 2\Delta \omega_2 \pm \Delta \omega_1)t + \dots$$

As a result, a multiple tremolo effect sound more intricate than the ones described above can be obtained.

In an example shown in FIG 4, a feed-back device FB₁ similar to that shown in FIG 1 is connected between the input side and the output side of a frequency deviation device FS₁, and in the same way a feed-back device FB₂ is connected between the input side

and the output side of a frequency deviation device FS₂. Therefore, when two frequency deviation devices FS₁ and FS₂ having frequency deviations $+\Delta f_1$ and $-\Delta f_2$ respectively are employed, the frequencies of output signals obtained at the output terminals *k* and *l* are $(f + \Delta f_1)$ and $(f - \Delta f_2)$ respectively. When a part of each output signal mentioned above is fed back to its respective input terminal *i* or *j* through its respective feed-back device FB₁ or FB₂, signals represented by the following formulas are obtained at the output terminals *k* and *l* respectively in the same way as in the case of FIG. 1:

$$\text{Terminal } k \quad a_2 \cos(\omega + 2\Delta\omega_1)t$$

$$\text{Terminal } l \quad b_2 \cos(\omega - \Delta\omega_2)t$$

These signals are fed back to the input sides respectively, and the signals of $a_3 \cos(\omega + 3\Delta\omega_1)t$ and $b_3 \cos(\omega - 3\Delta\omega_2)t$ are obtained at the output sides respectively. By repeating the feed-back operation in the sameway, signals represented by the following general formulas can be obtained.

$$\text{Terminal } k \sum_{i=1}^n a_i \cos(\omega + i\Delta\omega_1)t$$

$$\text{Terminal } l \sum_{i=1}^n b_i \cos(\omega - i\Delta\omega_2)t$$

where a_i and b_i are signal amplitudes.

As shown in FIG. 5, the frequency spectrum of these signals shows many frequencies (side band frequency) spread at the intervals of Δf_1 and Δf_2 on the both sides of the musical sound frequency (*f*). These signals are fed to the output terminal *m* through resistors R₄ and R₅ and then are mixed with an original musical sound signal furnished through a resistor R₃, thereby to obtain a signal represented by a formula below:

$$B \cos \omega t + \sum_{i=1}^n \{a_i \cos(\omega + i\Delta\omega_1)t + b_i \cos(\omega - i\Delta\omega_2)t\}$$

where *B* is the amplitude. This signal is obtained by combining the signal which frequency is (*f*) and a signal which is deviated by as much as Δf_1 or Δf_2 on the both sides of the frequency (*f*). Therefore, the musical sound signal can be considered as a multi-rank sound consisting of a multi-sound source. Moreover, to this signal the effects of amplitude-modulation and phase modulation are added, whereby an intricate tremolo effect can be obtained.

In the above description, the frequency characteristics of the feed-back devices FB₁ and FB₂ are not explained. However, if the frequency characteristic is made to have specially great attenuation in the low frequency components, the envelope of a high frequency spectrum will be widened in respect of the overall characteristic. This is more effective for a sound which is rich in higher harmonics as found in a string musical instrument. It is possible to select feed-back devices having various characteristics other than described above, in order to obtain various effects on sound.

In the above description, Δf_1 is not equal to Δf_2 . However, if Δf_2 and Δf_1 are such in value that if one is an integral multiple of the other, high frequencies arranged at an interval of Δf_2 in a lower side band suppress those arranged at an interval of Δf_1 in the lower side band, thereby to reduce the effect on sound. Therefore, it is desirable to so select the values of Δf_1 and Δf_2 that one is not an integral multiple of the other.

Further, it is explained in the above description that the musical sound signal frequency is deviated either higher or lower by as much as the extremely low frequency Δf_1 or Δf_2 in the respective frequency deviation devices FS₁ and FS₂. However, it is possible to simultaneously deviate the frequency higher and lower by as much as Δf_1 , or Δf_2 by employing a two side band modulation. The frequency spectrum of the output signal in this case becomes much more intricate than that in FIG. 5. As a result, a much higher tremolo effect can be obtained.

While a few embodiments of the present invention have been illustrated and described in detail, it is particularly understood that the invention is not limited thereto or thereby.

I claim:

1. An electronic tremolo effect producing device which comprises: a musical sound signal circuit generating a musical sound signal; a first frequency deviation means connected to said musical sound signal circuit for deviating the frequency of said musical sound signal frequency by as much as a first deviation frequency sufficiently lower than the frequency of said musical sound signal; a second frequency deviation means connected to said musical sound signal circuit for deviating the frequency of said musical sound signal frequency by as much as a second deviation frequency which is sufficiently lower than the frequency of said musical sound signal and is different from said first deviation frequency; a first feed-back means connected to feed back a part of the output of said first frequency deviation device to an input side of said second frequency deviation means; and a second feed-back means connected to feed back a part of the output of said second frequency deviation means to an input side of said first frequency deviation means, output signals from said first frequency deviation means and said second frequency deviation means being combined with said musical sound signal thereby to obtain a tremolo effect signal.
